(57) **CLAIM**

The ornamental design for a dog harness, as shown and described.

DESCRIPTION

FIG. 1 is a top, rear, right perspective view of a dog harness, showing my new design in condition of use;

FIG. 2 is a top, front, right perspective view of the dog harness of FIG. 1, shown enlarged for clarity of disclosure;

FIG. 3 is a top, rear, right perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines depict environmental subject matter only and form no part of the claimed design. The broken line on the harness depicts stitching and forms no part of the claimed design.
